CHARLES F. ALBRECHT, OF CLEVELAND, OHIO, ASSIGNOR OF TWO-FIFTHS TO BION D. FORD, OF CLEVELAND, OHIO.

SAFETY LOCKING DEVICE.

1,117,750.

Specification of Letters Patent. Patented Nov. 17, 1914.

Application filed April 20, 1914. Serial No. 833,008.

To all whom it may concern:

Be it known that I, CHARLES F. ALBRECHT, a citizen of the United States, residing at Cleveland, in the county of Cuyahoga and 5 State of Ohio, have invented a certain new and useful Improvement in Safety Locking Devices, of which the following is a full, clear, and exact description, reference being had to the accompanying drawings.

This invention relates to safety locking devices, and more particularly to devices of this character which are adapted for use with tools operated by fluid pressure, such as pneumatic hammers, drills, and air-operated rotary pistons. The particular embodiment of my invention disclosed herein is shown as applied to a pneumatic hammer and is arranged so that it will prevent the accidental displacement of the air-controlling valve in the handle, as by the unintentional impact of the trigger against the hand of the operator or against any other object. As is well known to those who are skilled in this art, accidents attended with 15 more or less serious results have resulted from the unintentional displacement of the valve in tools of the kind referred to, whereby the pressure fluid is admitted to the tool and the tool placed in operation at an inopportune time or in an inopportune place.

It is the general object of this invention to provide means whereby such unintentional operation in tools of this character may be prevented.

A further object of the invention is to secure this result in and through a particularly simple, economical, and efficient construction, which can be readily attached to and removed from tools of the character referred to with no material change in, or addition to, such tools.

I accomplish the foregoing and other objects, which may appear hereinafter, in and through the construction illustrated in the drawings forming part hereof, wherein—

Figure 1 represents a side elevation of the handle end of a tool of the pneumatic hammer type, a part of the handle and the coöperating parts being shown in section, 50 the valve being locked in closed position in

and through my attachment; Fig. 2 is a sectional detail of the handle, showing the parts of my locking device or attachment when released to permit the operation of the valve in the ordinary manner; Fig. 3 55 is a perspective view of my locking device or attachment; and Fig. 4 a sectional view through the locking device corresponding to the line 4—4 of Fig. 1.

Describing the various parts illustrated 60 herein by reference characters, 1 denotes the cylinder and 2 the handle of a tool of the pneumatic hammer type. The tool shown herein is of standard construction and contains the passageway 3 through 65 which pressure fluid is supplied to the cylinder 1 by means of a connection 4 which is adapted to receive the ordinary hose (not shown). The portion 2^a of the handle which is grasped by the operator is provided with 70 a bore 5 which intersects the passageway 3, and within this bore there is inserted a sleeve or bushing 6 having two sets of ports 7 and 8, the ports 7 communicating with the connection passageway 4^a and the ports 8 communicating with the passageway 3, the sets of ports being separated by an annular wall 9 which fits within and fills the bore 5.

For convenience of description, it will be assumed that the tool is operated in a vertical position, as shown in Fig. 1, and the terms "right" and "left" and "top" and "bottom" will be employed in accordance with this assumption. The upper left hand end of the handle part 2^a is provided with 80 a slot 10 through the upper part of which there extends a pin 11, to which the trigger 12 is pivoted. The upper part of the sleeve or bushing 6 may be cut away or slotted, as shown at 6^a, to receive therewithin the 85 valve-operating lug 13 of the trigger, the handle 14 of the trigger projecting outside of the slot 10, in position for convenient operation.

Reciprocably mounted within the sleeve 95 or bushing 6 is a valve, indicated generally at 15. This valve is provided with two cylindrical abutments 16 and 17, the abutment 16 being at the right hand end of the valve and the abutment 17 being spaced a sufficient 100

distance from the abutment 16 to provide, with the reduced connecting stem 15^a and the inclosing bushing or sleeve 6, an annular passageway 18 which extends between 5 and connects the ports 5 and 7 when the valve is moved to the right by the trigger 14,—in a manner well known to those familiar with this art. A spiral spring 19 which is within the right hand portion of the 10 sleeve or bushing 6 bears at one end against abutment 16 registering with the ports 7 against a block 20 which is threaded into the outer or right hand end of the sleeve or bushing and tends to hold the valve in the 15 position shown in Fig. 1, namely; with the abutment 16 registering with the ports 7 and cutting off the supply of pressure fluid to the passageway 3, the end of the valve which is opposite the abutment 16 bearing 20 against the lug 13.

The parts hereinbefore described and identified by the numerals 1 to 19 inclusive are of standard construction.

The block 20 constitutes a part of the 25 device or attachment which I employ for locking the valve 15 against displacement through an accidental operation of the trigger. The block projects outwardly beyond the sleeve or bushing 6 and is provided with 30 a cylindrical abutment 21. Near its outer end the abutment 21 is bored transversely, as shown at 22. The block 20 of which the abutment 21 forms a part is provided with 35 a central longitudinal bore for the reception of a hollow rod or tube 23 which is adapted to engage the adjacent end of the valve 16 and positively lock the valve in its cut-off position with reference to the ports 7, under circumstances to be described here- 40 inafter.

24 denotes an external sleeve which surrounds the abutment 21 and is provided with a bayonet slot 25, 26, the transverse portion 26 of the slot being located at the 45 right end or outer end thereof. This slot is adapted to receive therewithin a pin 27 which may be driven into the upper portion of the bore 22 and which pin is preferably of such length that its lower end will abut 50 against the hollow rod or tube 23. The outer or right hand end of the sleeve 24 is closed by a head 24^a to which the outer or right hand end of the hollow rod or tube 23 is secured, and the spiral spring 28 sur- 55 rounds the outer end of this rod or tube and bears at one end against the abutment 21 and at its opposite end against the head 24^a, tending to move the sleeve 24 and the attached tube or rod 23 outwardly and away 60 from the valve 15. For convenience of manipulation, the outer end of the sleeve 24 is knurled, as indicated at 24^b. By boring entirely through the abutment 21, the pin 27 may be easily backed out through the

said bore, the holes 23^a in the tube or rod, 65 and the hole 24^c in the lower portion of the sleeve.

From the foregoing it is believed that the operation will be apparent. When the operator finishes the particular work on 70 which he is employed, he grasps the sleeve 24 by the knurled or milled end thereof, pushes the sleeve and the attached tube or rod 23 inwardly until the pin 27 reaches the lateral portion 26 of the bayonet slot, whereupon he gives the sleeve a turn to the right, bringing the pin 27 into the lateral portion 75 of the slot, thereby locking the parts in the position shown in Fig. 1. In this position, it will be evident that the valve abutment 16 will completely cut off the flow of pressure fluid from the passageway 3 and that the valve 80 cannot be operated by pushing the trigger handle 14 inwardly, or to the right, either by accident or by design. In other words, 85 the operating movement of the trigger as well as the movement of the valve is completely blocked. When, however, it is desired to operate the tool, it is necessary only to turn the sleeve 24 a sufficient distance to 90 the left to bring the pin 27 into the longitudinal portion 25 of the bayonet slot, whereupon the spring 28 will throw said sleeve and the attached hollow rod or tube 23 to the right, as shown in Fig. 2. The 95 valve then may be operated in the usual manner by the trigger.

The blocking device 23 is bored or tubular to facilitate the opening of the valve by the trigger. Furthermore, a pin 23^b is carried by the device 23 to prevent the same from being forced out of the block 21 should the pin 27 happen to break or fall out.

From the foregoing it will be evident that I have produced a locking device for tools 105 of the character set forth which is extremely simple of construction and efficient in operation and one which can be applied to existing standard tools with no alteration thereof and with the mere addition of a small, simple and economical attachment thereto.

Having thus described my invention, what I claim is:—

1. A fluid pressure operated tool comprising, in combination, a barrel or cylinder, a handle for said barrel or cylinder provided with a passageway for pressure fluid, a valve in said handle adapted to control the flow of fluid through such passageway, a trigger carried by the handle for operating the valve, a device adapted to engage the valve and block it against movement by the trigger, means for retaining said device in blocking position, and a spring arranged to move said device out of 115 valve-blocking position when the said device is released.
2. A fluid pressure operated tool comprising

ing, in combination, a cylinder or barrel, there being a passageway for conducting pressure fluid to said cylinder or barrel, a valve movable transversely with respect to 5 said passageway to control the flow of fluid therethrough, a manually operated device for unseating said valve, a device adapted to engage said valve and prevent the unseating thereof, means for locking the last mentioned device in valve-engaging position, 10 and means for automatically moving the last mentioned device out of valve-engaging position.

3. A fluid pressure operated tool comprising, in combination, a barrel or cylinder, a handle therefor, said handle having a passageway for conducting pressure fluid to the barrel or cylinder, a valve in said handle controlling said passageway and normally 15 preventing the passage of fluid therethrough, a trigger carried by said handle and adapted to move the valve in a direction to permit the flow of fluid through the passage, a locking device for said valve, said 20 device comprising a member which is adapted to engage the end of the valve opposite said trigger, means for locking said member in valve engaging position, and a spring tending to move said member out of valve- 25 engaging position.

4. A fluid pressure operated tool comprising, in combination, a barrel or cylinder, a handle therefor provided with a passageway for supplying pressure fluid to the cylinder 35 or barrel, a bushing extending across said passageway and provided with one or more ports for admitting pressure fluid to the passageway, a valve in said bushing, a trigger carried by the handle and having a portion 40 adapted to engage the valve to move it in a direction to permit the flow of fluid through said port or ports, a locking device for preventing the movement of the valve by the trigger, said device comprising a body which 45 is carried by the end of the bushing opposite the trigger, a valve-engaging member slidably mounted in said body, a spring tending to move said member away from the valve, and means for locking said member in valve- 50 engaging position against the action of said spring.

5. A fluid pressure operated tool comprising, in combination, a cylinder or barrel, a handle therefor provided with a passageway, 55 a bushing intersecting said passageway and provided with one or more ports through which pressure fluid is adapted to enter the passageway, a valve reciprocably mounted within the bushing and controlling said port 60 or ports, a trigger carried by said handle and having a portion adapted to engage the valve and operate it in a direction to permit the flow of fluid through said port or ports, said trigger being located adjacent to one

end of said bushing, a locking device carried 65 by the opposite end of the bushing, said device comprising a body threaded into the bushing and provided with a longitudinal bore, a valve-engaging member slidably mounted in said bore and adapted to engage 70 the adjacent end of the valve, a sleeve having a head to which the outer end of the hollow rod or tube is secured, a spring interposed between said head and said body and surrounding the valve-engaging member, 75 and a pin carried by said body, the sleeve being provided with a bayonet slot coöperating with said pin to retain the valve-engaging member in its inwardly adjusted position against the action of said spring. 80

6. A fluid pressure operated tool comprising, in combination, a cylinder or barrel, said tool being provided with a passageway and with a bore intersecting said passageway, a valve reciprocably mounted within 85 the bore and controlling the passageway, means whereby said valve may be operated in a direction to permit the flow of fluid into said passageway, a locking device slidable within said bore and adapted to engage the 90 adjacent end of the valve, means for locking said device in such valve-engaging position, and a spring for moving said device out of valve-engaging position.

7. A fluid pressure operated tool comprising, in combination, a cylinder or barrel, said tool being provided with a passageway and with a bore intersecting said passageway, a valve reciprocably mounted within the bore and controlling the passageway, 100 means whereby said valve may be operated in a direction to permit the flow of fluid into said passageway, a locking device slidable within said bore and adapted to engage the adjacent end of the valve, a pin and bayonet- 105 slot connection between the locking device and the tool for retaining the said device in valve-engaging position, and a spring for moving said device away from said valve.

8. In a fluid pressure operated tool having 110 a bore for fluid under pressure, a valve reciprocably mounted within the bore and controlling the flow of fluid therethrough, means whereby said valve may be operated longitudinally of said bore in one direction 115 to permit the flow of fluid therethrough, a locking device which is slidably mounted within said bore and is adapted to engage the valve to prevent the movement of the same in a direction to permit the flow of 120 fluid therebeyond, means for locking said device in such valve engaging position, and a spring for moving said device out of valve engaging position.

9. A fluid pressure operated tool having 125 a passageway for pressure fluid, a valve controlling the flow of fluid through said passageway and movable in one direction to

permit the flow of fluid through such passageway, means for operating the valve in such direction, a blocking device movable in the same linear direction as the valve and adapted to engage the valve to prevent its movement in a direction to permit the flow of fluid through the passageway, means for locking said device in such valve blocking position, and a spring coöperating with said

device to move it out of valve blocking position. 10

In testimony whereof, I hereunto affix my signature in the presence of two witnesses.

CHARLES F. ALBRECHT.
